RUBBER HEEL WITH ROTATABLY
ADJUSTED SECTIONBenjamin Gilowitz, Bronx, N. Y., assignor of one-
half to Harry Litman, Bronx, N. Y.

Application March 17, 1953, Serial No. 342,839

14 Claims. (Cl. 36—36)

1

My invention relates to shoe heels of rubber of the type in which a circular section is set into the rear portion of the body of the rubber heel and may be rotatably adjusted when the rearmost portion of the section is worn down so as to present an unworn portion of the section at the rear of the heel where the greatest wear takes place in use of the shoe. In rubber heels of this type, the formation in the lower rear part of the body of a circular recess for the reception of the rotatably shiftable section, leaves at the sides of the bottom of the body two rearwardly tapered wings or corners which have a tendency to spring away from the peripheral edge of the circular section and to be caught on projecting portions of surfaces over which the wearer may walk. Various attempts have been made to prevent these generally V-shaped wings or projections from spreading outwardly and to hold them in close contact with the circular edge of the section but I know of none which have sought to solve the problem in the manner hereinafter described.

The main object of the invention is to provide on the tapered rear corners of the bottom of the rubber heel body, flexible inwardly extending anchoring members which overlie the circular section and are removably set into recesses in the bottom of the latter so that the tapered wings or corners will be effectively held in tight contact with the circular edge of the section.

Another object of the invention is to provide a rubber heel of this character which will leave the factory as an assembled unit ready to be applied to a leather shoe or its heel either at a shoe factory or at a shoe repair shop by simply driving a few nails.

Another object is to provide a rubber heel of this character in which the circular section when worn at one place may be rotatably adjusted or shifted by the shoe owner or a shoe repair man to present an unworn portion of the section at the rear of the heel.

Another object is to provide a rubber heel of this character to which a metal wear plate may be removably secured by one or more screw threaded fastenings, and which when applied to a leather heel will be hardly distinguishable from the ordinary one-piece rubber heel.

With the above and other objects and advantages in view, the invention resides in the novel combinations and arrangements of parts and the novel features of construction hereinafter described and claimed, and illustrated in the accompanying drawings which show the present preferred embodiments of the invention.

2

In the drawings:

Fig. 1 is a side view of the rear portion of a shoe showing the improved rubber heel applied;

Fig. 2 is a bottom view of the heel shown in Fig. 1;

Fig. 3 is a view similar to Fig. 2 with the circular section removed and one of the flexible anchoring members broken away;

Fig. 4 is a longitudinal section on line 4—4 in Fig. 2;

Fig. 5 is a transverse section on line 5—5 in Fig. 2;

Fig. 6 is a top plan view of the circular section shown in the above views;

Fig. 7 is a bottom plan view of a second form of the improved heel;

Figs. 8 and 9 are sectional views taken on the lines 8—8 and 9—9 respectively in Fig. 7;

Fig. 10 is a perspective view of the metal wear plate shown in Figs. 7 and 8;

Fig. 11 is a bottom plan view of a third form of the invention;

Figs. 12 and 13 are sectional views taken on lines 12—12 and 13—13 respectively in Fig. 11; and

Fig. 14 is a perspective view of a metal wear plate which may be applied to the heel shown in Fig. 11 as indicated by the dotted line therein, and which is shown in section in Fig. 12.

30 In the drawings I have shown three forms of the invention but in all of them flexible arms extend inwardly from the tapered corners to lie in radial recesses or channels formed in the bottom of the circular section, the arms being provided with lateral projections or lugs to enter a socket or sockets formed in the section. These arms and their projections or shouldered portions will be retained to some extent in the section by friction and by the resilience of the material but I prefer-

40 ably employ other fastening means which may or may not also assist in holding the section in its adjusted position in the recess of the body portion of the rubber heel. By the use of "rubber" herein it is to be understood that the material used may be natural rubber, synthetic rubber, resilient plastic or other rubber-like resilient material.

50 Referring more particularly to Figs. 1—6, the letter S denotes a portion of a shoe, boot or the like and H the usual leather heel to which the rubber heel is nailed or otherwise fastened. The improved rubber heel comprises a body 15 molded from resilient rubber-like material with a substantially circular recess 16 in the rear portion of its bottom for the reception of an adjustable circular wear section 17. The formation of the re-

cess 16 leaves two rearwardly tapered wings or corners 18 disposed along the opposite side edges of the section 17. The body 15 is moulded with the usual dished or concave top face (not shown) so that its edges will be in tight contact with the leather heel when nailed thereto. Usually five nails 19 are used and they are driven in holes 20 until their heads engage the usual washers 21 molded in the body. Provision is made whereby some of these nails are driven entirely through the rotatable section in any of its adjusted positions so that the assembled sectional heel may be fastened as a unit to the shoe.

Extending inwardly from the end portions of the tapered corners 18 are flexible anchoring members or arms 22 which are provided with laterally projecting lugs 23 preferably disposed at their free ends. These arms which may be straight or tapered, are alined transversely of the heel and are received in radially disposed recesses or channels formed in the bottom of the section 17 so that they will lie flush with the bottom of the heel. As shown in Fig. 2 these channels are formed by the end portions of a single diametrically extending channel 24, and hence this section 17 may be turned to either of two adjusted positions but in the other forms two diametrically extending channels at right angles to each other are provided so that the section may be adjusted to any of four positions. The arms 22 may be molded in one piece with the body 15 in which case they will also be resilient or they may be attached to the corners 18 in any suitable manner. As shown the arms are flat but at their outer ends they are formed with thickened portions or lugs 25 which extend inwardly from the tapered corners 18 to provide a substantial connection between these parts. These lugs or thickened portions 25 fit in similar shaped notches 26 formed in the peripheral edge of the circular section 17 to assist in holding the latter in an adjusted position. The notches 26 are at the ends of the channel or channels 24. Due to the resilience of the material, the arms and their outer lugs 25 may be sprung into and out of the channels and notches. The arms 22 may be of various lengths, and as shown in Fig. 2, they do not extend to the center of the section 17. In this form the lateral projections or lugs 23 are of cylindrical shape and are adapted to be sprung or snapped into circular holes 27 formed in the bottom of the diametrical channel 24. The shouldered engagement between the projections 23 and holes 27 will prevent endwise movement of the arms and hence hold the tapered corners 18 in proper engagement with the section 17.

Various additional means may be provided to hold the arms in overlapping engagement with the shiftable section 17. I may form the arms with nail holes with sockets to receive washers. As shown in Fig. 5 holes 28 may pass through the centers of the projections 23 and receive nails 29, the heads of which engage the washers 30 in the bottoms of sockets. These small nails may be driven into the body 15, and even further, into the leather heel but they are easily pried out when the section 17 is worn at one point and is to be shifted to another position. These parts also serve to hold the section 17 in its recess 16 but other means may be provided to accomplish that result. For example in molding the body 15, the bottom of the recess 16 may be made rough as indicated at 31 in Fig. 3 and a similar roughened annular band 32 may be molded on the upper face of the section 17 as shown in Fig. 6; and then when

these parts are assembled a light coating of rubber cement may be applied to these contacting roughened areas. Or I may use at least one screw or bolt to fasten the section 17. As shown in Fig. 4, the section may have a central hole 33 to receive a bolt 34 which passes through a hole at the center of the recess 16 and engages a nut 35 molded in the body or set in a similar shaped socket molded in the top of the heel body. Or an annular series of holes 36 may be formed in the section 17, one of which may receive a suitable fastening. The number and arrangement of the holes 36 is such that in either of the two positions of the section 17, three of these holes will register with the three rearmost holes 20 so that the nails 19 may be driven through them and into the leather heel, as will be apparent upon reference to Fig. 4.

The embodiment shown in Figs. 7, 8 and 9 is quite similar to the first form and the same numerals with exponents will be used to designate the corresponding parts. The principal difference is that the arms 22^a are made longer so as to abut each other at the center of the heel and the projections 23^a are of rectangular shape so that both may be snapped into a square hole 27^a at the center of the section 17^a and fill the same. Further, two of the diametrical channels 24^a at right angles to each other are provided so that the section may be adjusted to four positions. The nail holes 28^a are formed in the intermediate portions of the arms instead of near their ends, and the arm fastening nails 29^a engage washers 30^a embedded in those portions of the arms as seen in Fig. 9. These nails 29^a also pass through holes 39 in the section 17^a and holes 40 in the body, there being four of each of the holes 39 and 40 so spaced that in any adjusted position of the section the holes 28^a will register with certain of the holes 39, 40. The nails 29^a may therefore be driven into the leather heel after the rubber heel has been fastened thereto but these nails may be readily pried out when the section 17^a is to be set in a new position. The five holes 20^a for the heel fastening nails 19^a are arranged differently in this form. The three rearmost holes 20^a are disposed so that they will be opposite the crossed grooves 24^a in the different positions of the section 17^a, and hence the latter is formed with only four equally spaced holes 36^a. The arms 22^a have holes 41 so positioned that they will register with two of the holes 36^a in any adjusted position of the section 17^a. The registering of three of the holes 36^a with the three rearmost holes 20^a permits the nails 19^a to be driven into the leather heel while the rubber heel is an assembled unit. While the bottom area of the body 15^a in rear of the recess 16^a may, in this form, be made plain as in the first form, I have shown shallow grooves 42 which produce anti-slipping cleats 43 at the bottom of the forward portion of the heel as seen in Fig. 7. I have also shown in Figs. 7, 8 and 10 a removable metal wear plate 44 which may be used if desired and which is disposed at the center of the rear of the heel. This heel plate is of right angular shape having a short upright arm 45 to fill the notch 26^a, which is at the center of the rear of the heel, and a long arm 46 which enters the adjoining channel 24^a, as seen in Fig. 8. The arm or branch 46 has a hole 47 which will register with the alined holes 39 and 40 that are rearmost to receive a fastener 48 such as a wood screw but which may be a bolt and nut similar to 34, 35. The plate 44 may have an additional hole 44^a to

register with the rearmost hole 36^a so that the rear nail 19^a may be driven when the plate 44 is on the assembled rubber heel. When the section 17^a is to be adjusted, the wear plate is of course removed but it may be replaced in the notch and channel that are rearmost in the new position of the section. In all other respects this second form is the same in construction and operation as the first form.

The third form shown in Figs. 11, 12 and 13 is quite similar to the second form since the rotary section 17^b has two intersecting and diametrically extending channels 24^b which also open into a single central hole 27^b formed in the section to receive both of the lateral projections 23^b on the flexible arms 22^b. However in this form the socket means, corresponding to the two holes 27 in the first form and the square or rectangular hole 27^a in the second form, is a circular hole 27^b and the lugs or projections 23^b which correspond to the previously described parts 23 and 23^a, are flat and enlarged circular heads disposed in superimposed relation in the socket means 27^b, as seen in Figs. 12 and 13. The flexibility of the arms 22^b permit first one head or projection 23^b to be snapped into the bottom of the hole 27^b and then the other to be snapped in on top of the first. The outermost head 23^b has its edge slightly cut-away at 50 in Fig. 11; and as shown at 51 in Fig. 13, it has a beveled portion to engage a corresponding beveled portion at the juncture of the lower or inner head with its arm 22^b. In this form the arms 22^b are not fastened by nails. Instead, a single fastener 52 corresponding somewhat to the bolt 34, is used to not only fasten the section 17^b in the recess of the body 15^b but also to fasten the two arms in position flush with the bottom of the heel. The screw passes through central openings in the heads or projections 23^b and a central hole in the center of the recess 16^b and into the leather heel as clearly shown in Figs. 12 and 13. In this form the section 17^b is also formed with four equally spaced holes 36^b which register with the three rearmost holes 20^b for the nails 19^b which fasten the rubber heel to the leather heel. To permit these nails to be driven with the parts assembled, the arms 22^b are also formed with holes 41^b which register with certain of the holes 36^b, as seen in Fig. 13. In Figs. 12 and 14 I have shown a metal heel plate 44^b, similar to the one shown in Fig. 10, which may be used with this third form. In Fig. 11 it is only shown in dotted lines. It consists of a thin sector-shaped plate with a thickened right angular part having an upright leg 45^b to fill the rearmost notch 26^b and a longitudinal leg 46^b to lie in the adjacent channel 24^b. The plate may also have a thickened portion 53 shaped to overlie one of the arms 22^b which is made a little thinner as shown at 54 in Fig. 13. When this heel plate is used the rearmost nail 19^b is replaced by a wood screw 48^b as shown in Fig. 12. The screw is inserted in a hole 47^b which registers with the rearmost holes 36^b and 20^b, and it is threaded into the leather heel. The plate is also shown with another hole 55 which registers with the hole 41^b in one of the arms 22^b so that a screw similar to 48 may be used to more securely fasten the heel plate.

It will be noted that in all three forms, the rotary section has channel means to receive the flexible arms and also socket means to receive the lateral projections on the arms, the socket means and the projections forming coacting shoulders which prevent the arms from moving outwardly and hence the tapered corners to which the arms

are united will be prevented from spreading away from the periphery of the section. When the arms are of resilient material the projections may be made to snap into the socket means, but whether resilient or not, all forms shown herein have some means for retaining the arms in the section when the heel is applied to a shoe.

While I have shown the rubber heel applied to a leather heel, it will be understood that the rubber heel may be made thicker and applied directly to the rear portion of the shoe sole.

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed.

I claim:

20. 1. In a rubber heel having a circular rotatably adjustable wear section set in a substantially circular recess in the rear of the bottom of a heel body, the latter having rearwardly tapered corners disposed at opposite side edges of the section, means for holding said tapered corners against outward spreading and securing them to the circular section, said means comprising a pair of flexible and resilient arms extending inwardly from said corners and having lateral projections, the bottom of said section having at least one radial channel to receive said arms and also having socket means into which said projections snap to prevent outward movement of said arms and outward spreading of said corners away from said section, means associated with said arms to removably retain them in engagement with said section.
25. 2. The structure of claim 1 in which said body has holes with embedded washers concentric therewith to receive nails for fastening the rubber heel to a leather heel, and in which said circular section has holes which align with certain of said nail holes when the section is in an adjusted position to enable the assembled rubber heel to be nailed to the shoe heel.
30. 3. The structure of claim 1 in which said circular section has at diametrical points in its edge notches which align with said radial channel and which receive thickened portions of said arms where they are united to said tapered corners.
35. 4. The structure of claim 1 in which said means removably retaining said arms in engagement with said section includes nail holes in said arms and washers embedded in said arms concentric with said nail holes.
40. 5. The structure of claim 1 in which said socket means consists of diametrically spaced holes in said circular section for reception of said projections.
45. 6. The structure of claim 1 in which said socket means consists of a centrally positioned hole in said circular section to receive both of said projections.
50. 7. The structure of claim 6 in which said projections on the arms are in vertically overlapping relation when in said central hole, and in which said means removably retaining the arms in engagement with the section consists of registering holes in the overlapped projections to receive a screw threaded fastening.
55. 8. The structure of claim 1 together with means retaining said circular section in an adjusted position in the recess of the body, the last mentioned means comprising a bolt positioned in a central hole in said section and passing through

an alined hole in said body, and a nut for said bolt seated in a socket in the upper face of said body.

9. The structure of claim 1 in which said circular section has diametrical notches in its peripheral edge at the ends of the channel, and in which said arms have thickened portions where they are united to said tapered corners, said notches receiving said thickened portions.

10. The structure of claim 1 in which said circular section is provided with two of said radial channels disposed at right angles to each other and either one of which may receive said arms in an adjusted position of said section, said section being also formed in its peripheral edge with notches alined with said channels, one pair of the diametrical notches receiving thickened portions of said arms where they are united to said tapered corners, according to the adjustment of said section.

11. The structure of claim 10 together with a metal wear plate having a portion to fill the notch at the center of the rear of the heel and to extend into the channel alined with such notch, said plate having an opening to receive a removable fastening for securing said metal plate.

12. In a rubber heel having a circular rotatably adjustable wear section set in a substantially circular recess in the rear of the bottom of a heel body, the latter having rearwardly tapered corners disposed at opposite side edges of the section, means for holding said tapered corners against outward spreading and securing them to the circular section, said means comprising

15 a pair of flexible and resilient arms extending inwardly from said corners and having lateral projections, the bottom of said section having at least one radial channel to receive said arms and also having socket means into which said projections snap to prevent outward movement of said arms and outward spreading of said corners away from said section.

13. In a rubber heel having a circular rotatably adjustable wear section set in a substantially circular recess in the rear of the bottom of a heel body, the latter having rearwardly tapered corners disposed at opposite side edges of the section, means for holding said tapered corners against outward spreading and securing them to the circular section, said means comprising a pair of flexible arms extending inwardly from said corners, laterally extending projections on said arms forming shoulders, said section having on its bottom channel means to receive said arms, and also having socket means to receive said projections and forming shoulders engaged by said first mentioned shoulders to prevent outward movement of said arms and spreading of said tapered corners away from the edges of said section.

14. The structure of claim 13 together with means associated with said arms for removably holding them in said section when the heel is applied to a shoe.

BENJAMIN GILOWITZ.
